SIGNAL SYSTEM FOR RAILROADS

Filed Jan. 18, 1926

Patented Nov. 29, 1927.

1,650,858

UNITED STATES PATENT OFFICE.

HAROLD B. WORSTER, OF KEOKUK, IOWA, ASSIGNOR OF ONE-HALF TO CLARENCE ROY FARMER, OF KEOKUK, IOWA.

SIGNAL SYSTEM FOR RAILROADS.

Application filed January 18, 1926. Serial No. 81,977.

This invention relates to improvements in signal systems for railroads, and is designed to be used in connection with a dispatcher's telephone system, which is now in common use, and which provides for placing a number of telephones along the railroad at various places, such as at the telegraph offices, blind sidings, telephone poles or wind breaks, these telephones being under the control of the train dispatcher in such a manner that he may ring any one of a number of such telephones at his will. This present system works all right when there is any one located at the telephone so the ring can be heard, but it is often desirable to get in touch with a train at other times than those when the train is at the station or open office.

It is the object of my invention to provide a signal system which may be used in connection with these telephones in such a manner that when any one of the telephones is rung, a predetermined number of signals will be automatically displayed at such positions along the side of the railroad that the engineer's or conductor's attention will be called to the fact that they are wanted on the near by telephone, at which time the train may be stopped and the telephone answered, thereby bringing the dispatcher in touch with the train. It is most desirable that these signal systems be placed near blind sidings or offices.

A further object is to provide a signal mechanism which may be easily and quickly attached to each of the dispatcher's telephones, and which will automatically operate signal devices located along the side of the railroad without the necessity of stringing extra communicating wires between the telephone and the dispatcher's office. The signal is so arranged that when once given, it will be automatically retained until the telephone has been answered, at which time the signal will be automatically discontinued.

My invention consists in the construction, arrangement and combination of the various parts of the device, whereby the objects contemplated are attained, as hereinafter more fully set forth, pointed out in my claim, and illustrated in the accompanying drawings, in which:

Figure 1 is a side elevation of my improved signal mechanism, one end being re-

moved, showing the manner in which it is applied to a dispatcher's telephone.

Figure 2 is a diagrammatical view showing one method of installing my improved system.

Referring to the accompanying drawings, I have used the reference numeral 10 to indicate the dispatcher's telephone cabinet, which is provided with a receiver hook 11 pivotally mounted in the usual manner, and designed to carry a receiver 12, said hook being moved by the weight of the receiver to its lower limit of movement. The numeral 13 indicates the binding post connected with the bell operating mechanism.

My improved mechanism comprises a casing 14 in which is mounted a solenoid 15 having conductor wires 16 which are connected to the binding posts 13 of the telephone at the same point where an extension telephone would be connected. Pivotally mounted above the upper end of the solenoid 15 is an armature 17, the movement of which may be limited by means of set screws 18. The free end of the armature 17 is provided with a spring 19 having a contact member 20 designed to coact with the contact member 21 rigidly secured to the casing 14. The spring 19 has at its inner end a binding post 22. A conductor wire 23 is secured to the binding post 22, while a conductor wire 24 is secured to the contact member 21. The said conductor wire 23 includes an electric battery 25. The conductors 23 and 24 have connected in parallel therewith a series of signal devices 26 which may be located alongside a railroad in the manner herein-after more fully set forth.

Secured to one side of the casing 14 is a second solenoid 27 having a vertically arranged and pivoted armature 28, the movement of said armature being limited by means of adjusting screws 29. The lower end of said armature is designed to rest normally adjacent to the free end of the armature 17 in the manner clearly shown in Figure 1. The solenoid 27 is provided with conductor wires 30 and 31, the wire 31 including an electric battery 32, and the wire 30 terminating in a contact member 33 secured to either the inner or outer surface of the casing 10 of the dispatcher's telephone. Said contact is so arranged that when the receiver 12 is removed from the hook 11,

the arm of the said receiver hook will be elevated and make engagement with said contact member 33. The free end of the wire 31 is connected with said receiver arm, 5 thereby establishing a current through the solenoid 27 when the said receiver arm 11 is at its elevated position of movement.

In Figure 2 I have illustrated a railroad, designated by the numeral 34, which is provided with a series of sidings 35, 36 and 37.

Opposite each of the said sidings is a dispatcher's telephone, designated by the numeral 38, 39 and 40. A telephone 41 is located in the dispatcher's office. These telephones are all connected in the usual manner, the connections from each telephone being indicated by the numeral 42. The dispatcher's telephone system is so arranged that he may ring the bell of either of the 20 telephones 38, 39 and 40. The signal lights 26 are arranged preferably in groups of three with one at each end of the switch, and another opposite the center of said siding. The signal lights at the ends of the sidings 25 may be located at any desired distance from the said sidings, preferably about a quarter of a mile.

The practical operation of my device is as follows:

Assuming that the dispatcher wishes to get in touch with a train entering the siding 35, then the bell of the phone 38 is rung, which will cause a ringing current to be passed through the solenoid 15 and through the conductors 16, which in turn will cause the armature 17 to be lowered and the contact 20 to be brought into engagement with the contact 21, establishing a current through the signal lights 26. The lower end of the 40 armature 28 will then be moved into position above the inner end of the armature 17 through the action of the spring 43, and thereby lock the armature 17 at its lower limit of movement and establish the circuit 45 through the signal devices 26. As the train approaches the siding 35, the conductor's attention will be called to the fact that he is wanted on the telephone, through the signals 26, after which he will go to the telephone 38, elevate the receiver 12, causing the lever 11 to be elevated and make contact with the member 33, which will establish an electric circuit through the solenoid 27, causing the lower end of the armature 28 to be moved 50 inwardly and to disengage the armature 17, the inner end of which will then be elevated by means of the spring 44, and the contacts 20 and 21 disengaged and the signals 26 automatically turned off. At the same time the

conductor operates the telephone in the usual manner to receive the dispatcher's orders, after which the receiver 12 is again placed on the hook 11 and the current through the solenoid 27 disconnected, permitting the lower end of the armature 28 to again rest 65 against the inner end of the armature 17. The telephones 39 and 40 may be operated in a similar manner when so desired by the dispatcher.

Thus it will be seen that I have provided 70 a signal system of simple, durable and inexpensive construction, which may be easily and quickly applied to the dispatcher's telephones without having to run any additional wires between the dispatcher's office and the 75 stations, and at the same time provides means whereby when a ringing current is established in any one of the telephones, a signal will be established near the adjoining siding, so that the conductor of the train 80 will know that he is wanted on the telephone, and provides means in connection therewith whereby the signal may be automatically turned off as soon as the telephone has been answered, thereby providing means whereby 85 the efficiency of the operation of the railroad will be increased as well as increasing the safety of the operation of the railroad with relation to human lives.

I claim as my invention:

In combination, a dispatcher's telephone having a movable receiver hook, a contact member designed to be engaged by said receiver hook as it is moved to its upper limit of movement, an electric solenoid connected 95 in the ringing circuit of said telephone, an armature designed to be actuated by said solenoid, an electrically operated signal device including an electric circuit, said circuit including a switch device actuated by the 100 movement of said armature, a second electric solenoid, an electric circuit for said second solenoid including said receiver hook and its coacting contact member, a pivoted armature for said second solenoid designed to 105 automatically lock the first said armature with its switch device in a closed position on establishing a ringing circuit in said telephone, and to establish a signal through said signal device, said second armature being 110 adapted to be disengaged from the first said armature upon movement of said receiver hook to permit said first armature to be moved to its normal position and the coacting switch member opened, substantially as 115 described and for the purposes stated.

HAROLD B. WORSTER.
